(57) **CLAIM**

The ornamental design for an oral care display, as shown and described.

DESCRIPTION

FIG. 1 is a perspective view of an oral care display showing our new design;

FIG. 2 is a right elevation view thereof;

FIG. 3 is a left elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is an enlarged top plan view thereof.

The dashed lines shown in the figures represent environmental subject matter and form no part of the claimed design.
